COLLAPSIBLE SCREEN

Jeremiah S. Culp and Ralph D. Culp, Mason
City, Ill.

Application October 11, 1932, Serial No. 637,334

1 Claim. (Cl. 45—106)

This invention relates to the broad class of burial accessories and appurtenances and has more specific reference to a structure which may be conveniently referred to as a collapsible screen.

More explicitly recited, the improved screen has reference to a foldable portable device for use in association with conventional supports for coffins.

10 In carrying the inventive conception into actual practice, we have evolved and produced a structural assembly which is sufficiently decorative to harmonize with the complete setting and which serves to adequately conceal the 15 sometimes unsightly wheeled carriage or other equivalent support with which it is used.

The purpose of the invention is to provide a screen of this character which is characterized by the requisite ornamental and utilitarian characteristics whereby to provide an unequalled achievement in this line of endeavor which we submit, may well be endorsed by and acceptable to the trade in that it serves effectively for show room display purposes and is equally well 25 adapted for use in the home of the deceased, burial parlors and the like, to add to the luxurious and sumptuous setting without becoming too lavish and conspicuous in visual aspect.

In the accompanying drawings, wherein like numerals are employed to designate like parts throughout the same:

Figure 1 is a perspective view of a conventional burial ensemble or setting showing the position assumed by the ornamental screen.

35 Figure 2 is an elevational view of the especially fabricated and finished screen or covering per se.

Figure 3 is a perspective view of the foldable or collapsible frame work utilized for supporting the covering illustrated in Figure 2.

40 Figure 4 is a fragmentary edge view of the frame structure.

Figure 5 is a horizontal sectional view taken approximately on the plane of the line 5—5 of Figure 3.

45 Briefly stated, the gist of the invention is predicated upon a knock-down portable assemblage of appropriately selected and co-ordinated parts especially proportioned and appropriately fitted for the purpose intended, said assemblage embodying a collapsible framework and a detachable ornamental covering or screen therefor, the structure as a whole being properly proportioned with respect to the coffin so as to occupy the space between the base of the latter 50 and the floor while surrounding the customary

support or truck in a manner to conceal the latter while being independent of attachment to the coffin or the support.

The ensemble forming the framework is composed of a plurality of hingedly connected sections or units. These are preferably in the form of light weight wooden frames. For sake of distinction the end frames (see Figure 3) are denoted by the numerals 6, while the frontal or body frames are distinguished by the numerals 7. Any number of such frames may be provided according to the size of the structure needed.

Each frame is of general rectangular configuration and it will be noted that the end frames 6 are smaller in proportion than the 70 frame 7 whereby to permit said frame 6 to swing in and out freely beneath the coffin providing the requisite clearance between the floor and the bottom of the coffin in order to facilitate application and removal of the structure.

75 The frames are joined together by double-acting hinges generally denoted by the numerals 8. The hinges are actually made up of pairs of canvas or leather straps. In other words, each hinge is made up of closely related straps 9 and 10 arranged in reverse order so that the connective or intermediate portions 11 are left free to saddle over or embrace a removable maintenance stick 75

12. As shown in Figure 5, this stick is square in 85 cross section. This provides for the double acting or reversible hinge effect whereby to permit the frame to be swung either in or out to permit proper placement and subsequent folding for transportation purposes. Thus the frame structure is characterized by compactness and convenience.

90 As a matter of convenience the portions 11 of the respective straps may be designated as opposed loops forming seats for reception of the 95 complementary sticks 12.

Under normal circumstances the body frames 7 are arranged in longitudinal alinement when in use while the end frames 6 are directed inwardly into converging relationship and at appropriate angles with respect to the frame 7 in order to render the frame structure self-supporting and sustaining. The covering or screen is denoted, as a unit, by the numeral 14. This is of proportions commensurate with the frame structure and of appropriate finish and texture to harmonize with the remainder of the setting with which it is used. Only the outer face thereof need be finished for requisite adornment. In other words, the inner face may be plain and so 110

constructed to permit it to be adequately attached to the frame structure for the temporary use to which the complete assembly is put.

It is thought from the foregoing description 5 that the advantages and novel features of the invention will be readily apparent.

It is to be understood that changes may be made in the construction and in the combination and arrangement of the several parts provided that 10 such changes fall within the scope of the appended claim.

We claim:

A collapsible screen for coffin supporting means comprising a plurality of open-work frames of 15

the same height, double hinges connecting the side edges of said frames together, a pair of end frames of open-work construction and of less height than the first mentioned frame, double hinges connecting a side edge of each end frame to a side edge of the adjacent frame, each end frame having its upper and lower edge spaced inwardly from the upper and lower edges of the first mentioned frames, and a cover connected to the frames and entirely covering the outer 85 faces thereof.

JEREMIAH S. CULP.
RALPH D. CULP.
